149,388

DESIGN FOR A FAUCET OR SIMILAR ARTICLE

Irwin W. Stratmore, Passaic, N. J., assignor to Ball Washing Machine Corp., Passaic, N. J., a corporation of New Jersey

Application November 14, 1946, Serial No. 134,769

Term of patent 3½ years

(Cl. D91—3)

To all whom it may concern:

Be it known that I, Irwin W. Stratmore, a citizen of the United States, residing in Passaic, county of Passaic, State of New Jersey, have invented a new, original, and ornamental Design for a Faucet or Similar Article, of which the following is a specification, reference being had to the accompanying drawings, forming a part thereof.

Fig. 1 is a perspective view of a faucet or similar article embodying my new design,

Fig. 2 is a top plan view thereof taken on line 2—2 of Fig. 1, and

Fig. 3 is another perspective view thereof.

I claim:

The ornamental design for a faucet or similar article, as shown.

IRWIN W. STRATMORE.
